UNITED STATES PATENT OFFICE.

JOHN E. MILLS, OF CHICAGO, ILLINOIS.

DEEP-WELL PUMP.

1,134,479.

Specification of Letters Patent.

Patented Apr. 6, 1915.

Application filed March 27, 1914. Serial No. 827,545.

To all whom it may concern:

Be it known that I, JOHN E. MILLS, a citizen of the United States, residing at Chicago, in the county of Cook and State of Illinois, have invented certain new and useful Improvements in Deep-Well Pumps; and I do hereby declare the following to be a full, clear, and exact description of the invention, such as will enable others skilled in the art to which it appertains to make and use the same.

My invention relates to pumps and more particularly to pumps suitable for raising water from deep wells.

One object of my invention is to provide a simple and compact pump of such shape as to be readily lowered into the bore of a well, and one that may readily be actuated by a vertical shaft.

Another object is to provide simple means for supporting both the propeller member of the pump and the sections of the shaft so as to relieve the lower end of the pump from the strain of their weight.

Further objects are to provide a propeller construction so designed as to direct the stream of water into the discharge pipe of the pump, and to provide a simple valve for checking a return flow of the water into the pump chamber in case of a stopping or slowing of the actuating portions of the pump.

In the drawings, Figure 1 is a fragmentary sectional view of a well casing and of the pumping mechanism housed thereby. Fig. 2 is a fragmentary sectional view of the upper end of the same casing and the parts carried thereby. Fig. 3 is a fragmentary elevation of the lower end of the shaft and of the propeller mounted thereon. Fig. 4 is a horizontal section through Fig. 1 along the line 4—4.

In the embodiment of the drawings, the pump of my invention is shown as used in connection with a well casing consisting of a vertical tube 1 equipped at its upper end with a cap 2 supporting an inner tube 3. The cap 2 is provided with an upward extension 4 housing a ball race 5 supporting a flange 6 threaded upon a vertical shaft 7 and locked against rotation upon the said shaft by a lock nut 8. The upper end of the shaft 7 extends through a cover 9 threaded upon the said extension 4 so that it may be connected to suitable means for rotating the shaft. The tube 3 is connected by suitable

couplings 10 to additional tube sections 11 of such number and length as may be required for the depth of the well, the lowest of the said sections being secured to the upper end 12 of a pump chamber 13. Mounted within the said end 12 is another ball race 14 supporting a collar 15 secured to the lower end 16 of the said vertical shaft. Interposed between the said lower end 16 and the upper end 7 are intermediate shaft sections being secured to each other by slip joints or tenons 18, which tenons afford interlocking formations for non-rotatably coupling the adjacent shaft sections while permitting a relative longitudinal motion of said sections to compensate for the expansion or contraction due to temperature changes.

Secured to the lowest section 16 of the vertical shaft within the said pump chamber 13 is a propeller member 19 having a plurality of blades 20 disposed in substantially spiral formation about the axis of the said shaft. The lower edge portions 21 of the said propeller blades are preferably curved in concave formation corresponding to the convex curvature of the upper end of a suction tube 22 secured to the bottom of the pump chamber 13. The said suction tube carries at its lower end a screen 23 and has mounted within it a spider 24 supporting a pivoted screw 25 engaging a conical recess in the extreme lower end of the rotating shaft, whereby the said shaft may be held accurately centered with respect to the pump chamber. However, the adjustment of the supporting flanges 6 and 15 with respect to the shaft is preferably such as to relieve the screw 25 of supporting the weight of the shaft and the propeller, so that the said pointed screw need only to act as a centralizing guide means for the rotating portion of my pump.

Radially disposed within the pump chamber 13 is a vertical web 26 having its lower end disposed close to the upper edge 27 of the propeller blades. This web serves as a deflector for intercepting the water propelled by the rotating blades 20, so that the said water will be directed through an opening 28 into a discharge pipe 29, which pipe extends within the casing 1 along-side the inner tube 11 and projects beyond the top of the cap 2 of the casing.

To provide for oiling the respective bearings of the pumping mechanism of my in-

vention, I equip the extension 4 of the cap member of my pump with an oil chamber 30 adapted to receive and store a supply of oil and to feed the same into the tubular bore 31 of the shaft through a transverse perforation 32 alining with the said oil chamber 30. Opposite the bearing portions 33 of each of the said couplings 10, and the ball races 14, the said shaft is provided with 10 transverse perforations 34 permitting the oil from the said inner tube 31 to flow to the said bearings and ball races. The shaft 1 has likewise a transverse perforation 35 alining with an oil chamber 36 disposed in 15 the pump chamber 13 above the propeller member of my pump and from which the oil may distribute itself to the adjacent bearings of the shaft, propeller member and pump chamber.

20 It will be evident from the above description that the pump of my invention may be used in wells of any desired depth by simply providing a sufficient number of the extension tubes and intermediary shaft pieces, and that by providing a corresponding number of the ball races and flanges mounted upon the respective portions of the shaft, the lower or operating member of the pump may be relieved of undue strain 25 and friction. It will also be evident that by curving the lower ends 21 of the propeller blades, the said blades can operate with a minimum of clearance within the pump chamber, thereby permitting the 30 stream of water to be efficiently directed against the deflector 26 and forced into the pipe 29. In case the speed of operation of the pump is reduced, or the pump is entirely stopped, or in case the flow of water through 35 the pipe 29 meets an unexpected resistance, the water in the said pipe will be prevented from returning into the pump chamber through the opening 28 by a flap 37 mounted at the upper end of the aperture 28, 40 which flap acts as a simple and effective check valve. However, I do not wish to be limited to this particular arrangement of the check valve, nor to the exact details otherwise disclosed herein, it being evident 45 that the same may be modified in many ways without departing from the spirit of my invention as shown in the appended claims.

The length of the screw, pitch of the 50 blades, etc., may obviously be increased or 55 diminished without departing from the in-

vention. And in place of one screw or propeller a plurality thereof may be mounted one above the other in the pump chamber as will be apparent. To insure a continuity of the oil-supplying duct or bore of the 60 jointed vertical shaft, the adjacent ends of the sections may be counterbored and fitted with tubes 38 connecting the said ends, as shown in Fig. 1, the said tubes being slidable with respect to at least one of said shaft sections. 65

I claim as my invention:—

1. In a pump, the combination with a plurality of vertical shaft sections in substantially axial alinement with each other, of a 70 tube housing said sections, and separate bearings carried by the tube and independently carrying said sections respectively; the consecutive sections being equipped at their adjacent ends with interlocking formations for 75 non-rotatably coupling said sections, the said formations slidably interfitting to permit relative motion of the coupled sections longitudinally of the latter to compensate for differences in the relative expansion and 80 contraction of the tube and the shaft sections.

2. In a pump, the combination with a plurality of vertical and hollow shaft sections in substantially axial alinement with each 85 other, of a tube housing said sections, and separate bearings carried by the tube and independently carrying said sections respectively; the consecutive sections being equipped at their adjacent ends with interlocking formations for non-rotatably coupling 90 said sections, the said formations slidably interfitting to permit relative motion of the coupled sections longitudinally of the latter, the bores of the shaft sections 95 being enlarged at the coupled ends of the latter; and oil tubes connecting the coupled ends of the shaft sections, each of said tubes being slidable with respect to at least one of the shaft sections coupled thereby and 100 housed at its ends by the enlarged bores of the said shaft sections.

In testimony whereof I have signed my name in presence of two subscribing witnesses.

JOHN E. MILLS.
